UNITED STATES PATENT OFFICE

139,880

DESIGN FOR A PLATE MAKING MACHINE

Fred A. Hacker, Cranford, N. J., assignor to American Type Founders, Inc., Elizabeth, N. J., a corporation of New Jersey

Application July 17, 1944, Serial No. 114,427

Term of patent 14 years

(Cl. D64—11)

To all whom it may concern:

Be it known that I, Fred Alvin Hacker, a citizen of the United States, residing in the city of Cranford, county of Union and State of New Jersey, have invented a new, original, and ornamental Design for Plate Making Machines of which the following is a specification, reference being had to the accompanying drawing, forming a part thereof, and in which

Figure 1 is a perspective view of a plate making machine in closed position showing my new design; and

Figure 2 is a perspective view thereof in open position, with the front panel omitted for convenience of illustration.

The rear wall of the device is substantially plain and the right-hand side as viewed in Figure 1 is substantially like the left-hand side shown in that figure.

I claim as my invention:

The ornamental design for a plate making machine, as shown and described.

FRED A. HACKER.
